UNITED STATES PATENT OFFICE.

JAMES DOBIE SCOULER, OF ST. JAMES, VICTORIA, ASSIGNOR TO GEORGE COLES, OF SAME PLACE, AND WILLIAM MCLEAN, OF MELBOURNE, VICTORIA.

SHEEP-SHEARING MACHINE.

SPECIFICATION forming part of Letters Patent No. 576,902, dated February 9, 1897.

Application filed October 16, 1896. Serial No. 608,962. (No model.)

To all whom it may concern:

Be it known that I, JAMES DOBIE SCOULER, engineer, a subject of the Queen of Great Britain, residing at Main Street, St. James, 5 in the Colony of Victoria, have invented Improvements in Sheep-Shearing Machines, of which the following is a specification.

This invention relates to those classes of sheep-shearing machines in which a cutter is reciprocated over and in contact with a comb through the medium of compressed air or other suitable motive fluid acting upon the vanes or blades of a horizontal rotating motor-wheel. Its object is to simplify and improve 10 the construction of such machines, so that they will work more smoothly without wasting so much power in friction and so that they may be more easily adjusted or taken to pieces when required.

It relates more particularly to the driving 15 mechanism and means of adjusting the tension of the cutter upon the comb.

This invention will be more easily understood on reference to the accompanying drawings, wherein—

Figure 1 is a vertical central section, and Fig. 2 a plan, of a sheep-shearing machine constructed according to this invention and showing the cover removed, while Fig. 3 is a 20 plan of the under side of the front portion of the cover of said machine, illustrating the arrangement of the cutter-adjusting devices. Fig. 4 is a side elevation, and Fig. 5 a plan, of the under side of the cutter-tension-regulating nut.

The same letters of reference indicate the same parts throughout the drawings.

A represents the base or main portion of the casing of the machine, while B represents 25 the upper part or cover of said casing. This latter is secured to the former by means of a stout set-screw or stud C, which also serves as the fulcrum of an oscillating operating-lever D, whereby the requisite reciprocating motion is imparted to the cutter E. The rear end of this lever D is formed with a slot d, or, if preferred, it may be forked, as will be readily understood. Inside this slot d works 30 an antifriction-roller F, which is mounted eccentrically upon the hub of a comparatively

large horizontal motor-wheel G, fitting closely within the rear end of the casing A, which is made circular at said rear end, as shown in Fig. 3, to receive it. This motor-wheel G is made with a groove g around its periphery, 55 and in said groove are arranged a number of approximately radial blades or vanes g', against which the motive fluid impinges, a flat ring g² being secured around their upper edges in order to strengthen and keep them 60 in place.

The wheel G is mounted upon two sets of antifriction-balls arranged as follows: Into the hub of said wheel is screwed a hardened bushing H, turned with inclined surfaces h h' 65 near each end and fitting within a recessed portion I in the bottom of the casing A, while through the bushing H and recessed portion I a set-screw or stud J passes and when in position is securely fastened by a lock-nut j. 70 The upper end of this set-screw or stud is made with a flaring head, thus forming an inclined surface j', corresponding to the surface h' in the upper end of the bushing H. Fitting around the set-screw or stud J and 75 resting upon the bottom of the cap I is a loose collar j², formed with an inclined surface corresponding with that marked h in the lower end of the bushing H. Between these two surfaces h j² work a number of small anti-friction hardened-steel balls K, and similarly 80 between the surfaces h' j' are other similar balls K'. By these means the motor-wheel G is free to rotate without much friction or vibration, and so prolongs the life of the machine. 85

The compressed air or other motive fluid is conducted to the rear end of the casing A through a suitable flexible wire-bound or other pipe and thence through a passage L, 90 provided for that purpose in the casing A, until near the front of the wheel G, where it is directed through an approximately tangential port l with considerable force against the vanes or blades g' of the motor-wheel G, afterward escaping through the narrow part of the casing forming the handle of the machine and out over the cutter and comb.

The requisite tension is kept on the forward end of the operating-lever D, so as to 100

hold the cutter E down with sufficient pressure upon the comb M by means of an oscillating tension-arm N, the rear end of which is formed with an upwardly-projecting stud 5 or pin n, passing up into a screw-threaded cap O, the lower end of which is formed with an inclined recess O', corresponding with a similar surface O² on the lower end of the stud or pin n, for the purpose of carrying a set of small antifriction-balls K². In a similar way its upper end is formed with an inclined recess O³, corresponding with an oppositely-inclined surface O⁴ on a nut or screw-threaded collar O⁵, secured by a small lock-nut O⁶ on the upper end of the stud or pin n, and between said inclined surfaces O³ O⁴ are arranged another set of balls K³.

The screw-threaded cap O is made in two parts, the upper of which O⁷ is screwed onto the lower part and has a milled head, as shown in Fig. 4, while the lower part is formed with a number of vertical grooves O⁸ at regular intervals, as illustrated in Figs. 4 and 5. With these grooves the forward end of a small horizontally-sliding spring-bolt P engages in order to retain the cap O in any position into which it may be turned, thus preventing the tension becoming accidentally slackened, owing to the vibration of the machine or otherwise.

The front end of the tension-arm N bears upon the end of the cutter-operating lever D, and is connected to it by a pin n', projecting upwardly from said lever and working within 35 a slot n² in the front extremity of said arm, this slot being provided to allow for the relative movements of the lever and arm as each one oscillates about its own pivot.

Having now particularly described and as-

certained the nature of my said invention and 40 in what manner the same is to be performed, I declare that what I claim is—

1. In a sheep-shearing machine, the combination with the casing, the comb, the cutter, and the oscillatory cutter-lever having a 45 pin n' projecting upward from its forward end, of the tension-arm N having in its forward end a slot n² engaged with said pin, an upward-projecting pin or stud n on the rear end of the tension-arm, a screw-threaded cap 50 O placed over and around said stud and having in its periphery vertical grooves O⁸, a spring-pressed bolt P to engage the grooves of said cap, and antifriction-balls between the stud and cap, substantially as described. 55

2. In a sheep-shearing machine, the combination with the casing, the comb, the cutter, and an oscillatory cutter-operating lever having its rear end formed with a slot d and its forward end provided with an upward-projecting pin n', of a tension-arm N pivoted at its rear end in the top of the casing and provided at its forward end with a slot n² 60 engaged with pin n', means for adjusting the pressure of the tension-arm, a horizontally-mounted motor-wheel having its periphery provided with vanes, ball-bearings for the hub of said wheel, a friction-roller mounted eccentrically on the hub of the motor-wheel and engaged in the slot of the cutter-operating lever, and means for conducting a motive fluid to the vanes of the motor-wheel, substantially as described. 65 70

JAMES DOBIE SCOULER.
